UNITED STATES PATENT OFFICE

WILLIAM HENRY NOWN, OF LEICESTER, ENGLAND, ASSIGNOR TO UNITED SHOE MACHINERY CORPORATION, OF PATERSON, NEW JERSEY, A CORPORATION OF NEW JERSEY

LUBRICATING DEVICE FOR NEEDLES

Application filed March 22, 1927, Serial No. 177,281, and in Great Britain April 5, 1926.

This invention relates to lubricating devices for the needle or other work-engaging part of sewing machines and is particularly concerned with needle lubricating devices for 5 wax-thread sewing machines. Machines of this type are frequently provided with devices for lubricating their needles in order to prevent wax from adhering thereto, to reduce the friction of the needle in its guide and to 10 facilitate the passage of the needle through the work.

The particular object of the present invention is to provide a device for lubricating the needle of a wax-thread sewing machine which 15 will be simple and effective in use, will not require attention otherwise than preliminary adjustment on the part of the operator, will last without renewal for a considerable period, will economize in oil and will prevent oil 20 from accumulating on the operative mechanism of the machine when it is standing idle.

One feature of the invention consists in the provision of mechanism for relatively moving the needle and the lubricating device 25 or pad to secure a constant and efficient lubrication of the needle without at the same time subjecting the pad to excessive wear.

Another feature of the invention is in a curved needle sewing machine which comprises a curved needle, a lubricating device for the needle, a reservoir for the lubricant and means for controlling the supply of lubricant from the reservoir which is rendered operative to supply the lubricating device 35 only when the machine is in operation.

The above and other features of the invention will become apparent from a consideration of the following description, with reference to the accompanying drawing, of one 40 form of lubricating device according to the present invention as applied for example to an outsole stitching machine of the type described in the patent to Topham, No. 1,129,760, dated February 23, 1915.

In the illustrative form of device just referred to an oil reservoir 1 of the ordinary drip-feed or other convenient type is positioned in a convenient location upon the machine head and is connected by a duct 2 to a 45 delivery pipe 3, the lower end of which ter-

minates somewhat above the needle 4 and in the same vertical plane. Situated behind and to one side of the needle is a cam-actuated arm 5 pivoted on a shaft 6 by which the presser foot of the machine is raised and lowered during each cycle of the sewing operations of the machine. To the sleeve of this arm there is now secured a second arm 7 which has at its forward end an upright bore in which is held a pad 8 of felt or other absorbent material that projects a little below the under surface of the arm. As the cam-actuated arm 5 rocks about its shaft to raise and lower the presser foot the arm 7 carrying the felt pad will be raised to the lower end of the oil delivery pipe 3 and lowered to press against the upper side of the needle 4.

The timing of the cam-actuated arm 5 requisite to move the presser foot up and down as desired gives a motion to the pad arm 7 such that the pad is lowered upon the top of the needle just behind the needle guide indicated at 9 when the needle is at the top of its stroke, presses upon it with unvarying pressure while it makes part of its forward stroke and then rises to allow the passage of the needle holding jaws, indicated at 10, without contact between the latter and the pad.

In the stem 11 of the reservoir 1 is formed a cylindrical guideway 12 extending diametrically across the oil duct 2. In this guideway slides a solid plunger 13 having a port or cylindrical passage 14 bored through it so that when this port 14 is in alignment with the duct 2 a free passage for the oil is 85 formed therethrough, but not otherwise.

The plunger 13 is connected by any suitable means such as a Bowden wire 15 to an arm 16 which is the equivalent of the bell-crank lever 13 of the patent to Topham, No. 1,129,760 above referred to, being actuated when the machine stops to release the tension on the thread and again upon starting the machine to apply the tension. The movements of the arm 16 cause the plunger 13 to shoot across the duct 2 under the influence of the spring 17 just before the machine starts and act to withdraw the plunger again when the machine stops. Its passage across the duct as the machine is tripped to commence

sewing is quite rapid so that little or no oil can pass through its port 14 but as the machine is stopping the plunger 13 is withdrawn more slowly (as will be understood by reference to aforesaid specification) allowing oil to pass through the port 14. Any oil that may be in the delivery pipe 3 will not flow out unless the port 14 in the plunger 13 is in line with the duct 2 as the plunger 13 is an air-tight fit in its guideway 12.

When the machine has stopped the plunger 13 is in its most rearward position (as shown in the drawing) and the supply of oil is cut off, thus preventing accumulation of the latter upon the needle and surrounding parts. By changing the size of the port 14 in the plunger 13 the amount of oil delivered at each stroke of the plunger can be regulated. If a very small quantity only of oil is required the port may be of very small diameter, if a larger quantity is required the port may be larger in diameter or it may take the form of an elongated slot.

It will of course be understood that any suitable valve, slide or cock may be substituted for the plunger above described and that the means for automatically operating the same may be widely varied.

The nature and scope of the invention having been indicated, and an embodiment of the invention having been specifically described, what is claimed is:

1. In a sewing machine the combination with a curved needle, of a lubricating pad adapted to make contact with the needle, an actuator carrying the pad and movable to bring the pad into contact with the needle, and means acting in timed relation to the stitching operation to cause the actuator to move the pad from a position out of contact with the needle against the needle while the needle is stationary at the top of its stroke, continue the pressure during a portion of the down stroke of the needle, and then to raise the pad.

2. In a sewing machine the combination with a curved needle, of a lubricating pad adapted to make contact with the needle, a reservoir for supplying the pad, and means actuated only in starting and stopping the machine for controlling the supply of lubricant from the reservoir to the pad.

3. In a sewing machine the combination with a curved needle, of a lubricating pad adapted to make contact with the needle, a reservoir for supplying the pad, and means actuated only upon throwing the machine into and out of operation for controlling the supply of lubricant from the reservoir to the pad to supply the pad only for a short interval regardless of the number of stitching cycles in the operation.

4. In a sewing machine provided with means for placing a tension on the thread upon starting the machine and for releasing

the tension upon stopping the machine the combination with a curved needle, of a lubricating pad adapted to make contact with the needle, a reservoir for supplying the pad, and means controlled from the thread tensioning means for controlling the supply of lubricant from the reservoir to the pad to supply the pad only during the operation of the machine.

5. In a sewing machine the combination with a curved needle, of a lubricating pad adapted to make contact with the needle, an actuator carrying the pad and movable to bring the pad into contact with the needle, and means acting in timed relation to the stitching operation to cause the actuator to press the pad against the needle only during the movement of the needle in one direction.

In testimony whereof I have signed my name to this specification.

WILLIAM HENRY NOWN.
